ATTORNEY.

UNITED STATES PATENT OFFICE

SARAH E. SCHLOTT, OF ST. PAUL, MINNESOTA

PRESERVING JAR HANDLING MEANS

Application filed May 12, 1930. Serial No. 451,820.

My invention relates to devices for handling preserving jars of the well known type made usually of glass formed with a reduced diametral neck with exterior threads adapted to receive a metal cap. These types of jars in variable sizes are usually provided with but one size of opening and standardized thread means. The main body of such jars is usually round in cross section but some 10 are made square in cross section with generously rounded corners as shown in Fig. 4, but my device is adaptable for use on either type.

The main object is to provide handling 15 means of clamp type, readily placed around the body of a jar below its threaded opening and further means of like type readily engaging the exterior threaded part of a metal cap, the two devices cooperating in 20 use when placing a cap on the jar or removing such cap.

In the accompanying drawing,—

Fig. 1 is a top view of a round type preserving jar of the class mentioned, with its 25 cap in place, and my improved clamp means in operative position.

Fig. 2 is a front view of Fig. 1.

Fig. 3 is an enlarged transverse sectional view as on line 3—3 in Fig. 1 and including 30 parts as above line 4—4 in Fig. 2 only.

Fig. 4 is a modified sectional view as on line 4—4 in Fig. 2 showing a jar of the type which is approximately square in cross section and a jar clamp of corresponding form.

Fig. 5 is an enlarged detail sectional view 35 of the upper right hand part of Fig. 3 as between the lines A—A, more clearly illustrating certain details of the jar-cover clamp.

My improved jar and cover handling means 40 comprises a pair of clamp members one to engage a jar cap and the other to engage the jar body. Both are alike in action; namely, that their handles are squeezed toward each other to cause the clamp parts to frictionally 45 engage the jar cap and jar body as will now be fully described.

6 designates a preserving jar of the well known type having a cylindrical body and reduced at its top end to a circular flange 6A 50 above which the integral neck of the jar is

formed of glass and having a reduced neck 6B and a flange 6C. The exterior of the neck 6B is provided with threads 6T. The exterior of the flange 6C is provided with threads 6T.

7 is the usual jar-ring of rubber or other suitable material adapted to fit on the upper

face of flange 6A and to be pressed down 55 thereon by the lower outwardly directed flange 8F of the metal cap 8 threaded to be screwed on the jar top and fitting the threads 6T.

The square type of jar shown in Fig. 4 60 is designated 6', the threaded opening of this type of jar (not shown) being assumed to be the same as shown in Figs. 1, 2 and 3.

9 in Fig. 3 is the usual glass lining retained in the cap 8.

In Figs. 1-3 inclusive 10 designates an open metal loop of sheet metal and formed with threads 10T conforming to the threads of cap 8 and adapted to be engaged on said latter threads by simply first spreading the 70 loop by means of its integral handles 10H extended radially from its ends, then allowing the device to contract and engage the cap threads frictionally. This handle device is formed at its lower loop part with a downwardly extending short perimetral flange 10F of such size as to engage and inclose the lower perimetral flange or edge designated 75 8F, of the cap 8, (see Fig. 5).

After applying the cap tightener member 80 to the cap as just described, and assuming the cap has been threaded on the jar top loosely, above the packing ring 7, the operator grasps the handle members 10H squeezing them toward each other and the ring part 10 clamps the cover 8. Then turning the cap by clockwise movement the cap is brought down as tight as necessary. The flange 10F of the handle prevents flange 8F from curling upwardly or becoming uneven because of pressure exerted. The cap handling device is then easily removed by simply spreading it. Removal of a cap is accomplished by a reverse action to that just described.

The other co-operating device of my jar 95 means comprises another contractile handle device comprising a comparatively wide, open band-loop 11L with a pair of integral radially extending handles 11H, the loop being of such size as to be first spread, slipped 100

over the jar body and then allowed to contract and frictionally embrace the jar. 11B are a series of inward impressions or indentations of the band 11L providing friction means 5 adapted to catch or engage between the parts of raised letters 12 usually formed on the outer surface of preserving jars.

The handles 11H are clamped by one hand to contract loop 11L and hold the jar firmly, 10 as with a left hand designated 13 in Fig. 1, while a right hand as 14 is used to screw the cap 8 on tight. The larger handle device just described may of course be used independently to engage and lift jars 6 out of a 15 steaming device or out of any container partly filled with hot water as is often the case in the process of preserving. The jars and caps need not be handled with cloths or by hand as hitherto done.

20 I have shown both handle devices made each of a single piece of metal, the handle parts of which may be semi-tubular in cross section but other handle means, suitably formed and of other material than metal may 25 be used.

I claim:

30 In a jar cap manipulating device of the class described, comprising a clamp formed of flat metal stock with a loop part threaded 35 interiorly to engage a correspondingly threaded jar-cap, and a pair of integral handles extending approximately radially from said loop, the latter comprising in part a lower outwardly flared flange terminating at its 40 perimeter in a downwardly directed rim flange to form a guard for the lower rim of the jar cover.

In testimony whereof I affix my signature:

SARAH E. SCHLOTT.
